UNITED STATES PATENT OFFICE.

ERASTUS J. WHITE, OF LOCKE, NEW YORK.

WHIFFLETREE.

SPECIFICATION forming part of Letters Patent No. 250,609, dated December 6, 1881.

Application filed August 27, 1881. (No model.)

To all whom it may concern:

Be it known that I, ERASTUS J. WHITE, of Locke, in the county of Cayuga and State of New York, have invented certain new and useful Improvements in Whiffletrees; and I do hereby declare that the following is a full, clear, and exact description of the invention, which will enable others skilled in the art to which it appertains to make and use the same, reference being had to the accompanying drawings, which form a part of this specification.

Figure 1 is a plan view of my improved whiffletree. Fig. 2 is a horizontal sectional view of the same, and Fig. 3 is a front view. Similar letters of reference indicate corresponding parts in all the figures.

This invention relates to whiffletrees; and it consists in certain improvements in the construction of the same, which will be hereinafter fully described, and particularly pointed out in the claims.

In the drawings hereto annexed, A represents a flat plate or bar, which may be the cross-bar of a pair of thills, at or near the ends of which the ends of a flat slightly-curved spring, B, are secured by means of bolts C, passing through eyes D at the ends of said spring, the curve of which is in a rearward direction.

Secured by means of a bolt, E, to the center of spring B is another flat curved spring, F, provided at the ends with suitably-constructed trace-hooks G. Each of the springs may be constructed of a single or of a series of plates, the latter being preferable, in order to insure strength and elasticity.

H is a spring-rod, the ends of which are secured upon the bolts C, and which is provided

or formed with a centrally-located eye, I, which serves as a means of attachment when the device is to be used as or in connection with a double-tree.

J are guard-loops pivoted upon the bolts C, to prevent the traces from slipping off.

The operation and advantages of my invention will be readily understood from the foregoing description, taken in connection with the drawings hereto annexed. It is simple, light, inexpensive, and by its elasticity contributes much to easy riding. It also greatly relieves the horse of the shock caused by sudden starts. By a slight and easily apparent change the device may be advantageously applied as a neck-yoke.

Having thus described my invention, I claim and desire to secure by Letters Patent of the United States—

1. A whiffletree consisting of two flat curved springs bolted together centrally, one of said springs having its ends bolted to a rigid bar, and the other being provided at the ends with suitable trace-hooks, substantially as shown and specified.

2. As an improvement in whiffletrees, the combination of the springs B, F, the bar A, the rod H, having eye I, and the guard-loops J, all arranged and operating substantially as herein described, for the purpose shown and specified.

In testimony that I claim the foregoing as my own I have hereto affixed my signature in presence of two witnesses.

ERASTUS J. WHITE.
